UNITED STATES PATENT OFFICE.

GEORGE GRANTHAM BAIN, OF NEW YORK, N. Y.

PRINTING APPARATUS.

1,012,585

Specification of Letters Patent. Patented Dec. 26, 1911.

Application filed February 18, 1910. Serial No. 544,582.

To all whom it may concern:

Be it known that I, **GEORGE GRANTHAM BAIN**, a citizen of the United States, residing at No. 32 Union Square east, in the city, county, and State of New York, have invented new and useful Improvements in Printing Apparatus, of which the following is a specification.

This invention relates to printing apparatus, and more especially to apparatus of this character adapted for use in the printing of photographs.

One of the objects of the invention is to provide an apparatus of this character which will be inexpensive and simple in its construction.

Another object is to provide a device of this character which may be operated by unskilled persons, and which is largely automatic in its operation.

Other objects will be in part obvious and in part pointed out hereinafter.

In the accompanying drawing showing an illustrative embodiment of this invention, and in which the same reference numeral refers to similar parts in the several figures;

Figure 1 is a perspective view of the apparatus with the parts in the position they occupy during the printing process. Fig. 2 is a plan view thereof, parts being broken away for the sake of clearness. Fig. 3 is a vertical longitudinal section of the device with the parts shown in the position they occupy during the printing process. Fig. 4 is a sectional view of a part of the apparatus similar to Fig. 3 showing the position of the parts before or after printing. Fig. 5 is a perspective view of the printing frame. Fig. 6 is a detailed perspective view of a part of the back closing means. Fig. 7 is a diagrammatic view illustrating the method of closing the electric light.

In the illustrative embodiment of this invention shown in the drawings, 1 indicates a suitable frame provided with front and rear compartments 2 and 3, the tops of which are open. Adjacent the upper edge of the compartments at both sides thereof are guideways 4 upon which the printing frame 5 is adapted to slide, whereby it may be moved back and forth to register with the opening of either compartment, as shown in Figs. 3 and 4. The printing frame is preferably provided with a hinged back 6 having one or more springs 7 secured thereto to

which springs a bar 8 is attached in any suitable manner. The ends of the bar are preferably notched, as indicated at 9 in Fig. 5 to receive projecting portions 10 of arms 11 which are pivotally mounted upon the frame, as clearly shown in Figs. 2, 4 and 5. In the embodiment shown the arms are pivoted to the side walls of the frame which are shown extending above the rear compartment. The arms 11 may be secured to the bar 8 in any suitable manner, as for example, by hooks 12 carried by the arms engaging eyelets 13 in the bar. A handle 14 is preferably secured to the frame 5 at the front thereof in order that the operator may readily move the same into registry with one or the other compartments for the purpose hereinafter described.

From the foregoing description, it will be understood that as the printing frame 5 is drawn forward into registry with the opening in the front compartment 2, the pivoted arms 11 which are attached to the bar 8 will cause the back 6 of the frame to open and occupy the position shown in Fig. 4. In this position the frame is ready to receive the negative and the sensitized paper. After these are put in place, the frame is pushed toward the rear of the frame, sliding upon the guideways 4 and the back 6 will be closed through the agency of the arms 11 to occupy the position shown in Fig. 3, the arms 11 being so proportioned that when the frame is in this position there will be a certain amount of tension upon the springs 7, thereby holding the back firmly closed without, however, running any danger of breaking the glass, or otherwise injuring the frame. A cover 15 is preferably provided against which the back 7 of the frame 5 rests when in its open position and which assists in the closing of the back as the frame is pushed toward the rear of the apparatus.

Positioned within the front compartment 100 is a source of illumination such as an electric light 16 which is adapted to emit a light of such a character that it will not affect the sensitized paper. This may be accomplished by providing a lamp the glass of which is 105 ruby colored. This lamp is preferably kept lighted during the operation of the device, being in the present instance, connected by wires 17 direct to the main 18. In the rear compartment there is positioned one or more 110

sources of illumination suitable for printing purposes, being preferably incandescent electric lamps 16' as shown. One of the terminals of each of the lamps is connected 5 as by a wire 19 to one side of the main 18 and the other terminals of the lamps are connected to a contact 20, adapted to be electrically connected to a second contact 21 by a circuit closing member 22 secured to the 10 frame 5. The second contact 21 is electrically connected with the opposite side of the main 18 by a conductor 23. It will of course be understood that any other suitable circuit closing device may be used which 15 will operate to close the circuit when the frame registers with the opening in the rear compartment.

In order to vary the intensity of the light, which may be desirable when printing from 20 different negatives, means are provided for altering the positions of the lamps in the rear compartment with respect to the printing frame 5. In the present instance such means are shown as comprising bars or rods 25 24 slidably mounted within openings formed in the bottom of the rear compartment and openings formed in suitable cross-bars 25 carried by the frame 1. Each rod supports a lamp and is provided with a plurality of holes 26 within which a pin 27 is adapted to engage which pin rests upon the upper surface of its associated cross-bar 25. When it is desired to change the position of the lamp with respect to the printing frame 30 35 it is merely necessary to withdraw the pin 27, and lower or raise the rod 24 into the desired position, after which the pin may be inserted in the hole 26 which is positioned immediately above the cross-bar 25.

40 The operation of the device, which should be largely obvious from the above description, is as follows: When it is desired to make a print, the frame 5 is drawn forward into registry with the opening in the front 45 compartment 2, as shown in Fig. 4, in which instance, as above described, the back 6 is automatically opened. At this time the lamp 16' in the rear compartment 3 will be extinguished owing to the fact that the circuit is broken as above described. The ruby light 16 in the front compartment 2 is illuminated and by means of the same the film and the sensitized paper can readily be placed in position. The frame 5 is then 50 pushed inwardly into registry with the rear compartment 3 the back 6 closing automatically as described the instant the frame reaches such position the circuit of the lamps 16' within the rear compartment 3 55 will be completed thus causing them to be illuminated. By means of the automatic lighting of the lamps in the rear compartment the operator knows exactly the instant from which the exposure should be timed. 60 65 It is of course understood that the lights are

adjusted vertically into the proper positions before the apparatus is used. The printing frame is left in its position the required length of time necessary to make an exposure, and is then drawn forward. At the 70 instant the frame starts on its forward trip the circuit of the lamps in the rear compartment is broken, thus stopping the exposure immediately. The frame is drawn out into its forward position as shown in 75 Fig. 4 the back is automatically opened, and the sensitized paper and film are removed, thus completing the operation.

It will be seen from the above description that the apparatus is easily handled; 80 that it is very simple and not liable to go out of order and that owing to the automatic control of the lamps, it can be operated at a minimum expense. It will furthermore be seen that the timing of the 85 exposure can be accurately determined, inasmuch as the exposure does not begin until the frame is in its innermost position, and ends at the instant the operator withdraws the frame. 90

Having described this invention in connection with the illustrative embodiment thereof, to the details of which disclosure, the invention is not, of course, to be limited, what is claimed as new and what is desired 95 to be secured by Letters Patent is set forth in the appended claims:

1. In apparatus of the class described, in combination, a compartment having an opening, a printing frame adapted to register with said opening, an electric lamp positioned within said compartment, electrical contacts associated with said lamp and a contact maker carried by said frame and adapted to electrically connect said contacts 100 to illuminate the lamp when the frame is in registry with said opening. 105

2. In apparatus of the class described, in combination, a plurality of compartments provided with openings, a printing frame 110 adapted to be moved into registry with either one of said openings, said printing frame being provided with a movable back and rotatable means operatively associated with said back for automatically opening 115 said back when the printing frame is moved into registry with one of said openings.

3. In apparatus of the class described, in combination, two compartments provided with openings, a source of light in one of said compartments, said source of light being of such a character that the light emitted thereby will be free from rays adapted to affect sensitized paper, a source of light adapted to affect sensitized paper 120 positioned in the other of said compartments, a printing frame adapted to move into registry with either one of said openings, said printing frame being provided with a movable back and means for auto- 125 130

matically closing said back as said frame is moved into registry with one of said openings.

4. In apparatus of the class described, in combination, two compartments provided with openings, guideways associated with the openings of said compartments, a source of light in one of said compartments, said source of light being of such character that the light emitted thereby will be free from rays adapted to affect sensitized paper, a source of light adapted to affect sensitized paper positioned in the other of said compartments, and a printing frame mounted upon said guideways and adapted to be slid thereon into registry with either one of said openings.

5. In apparatus of the class described, in combination, a plurality of compartments provided with openings, a printing frame adapted to be moved into registry with

either one of said openings, said printing frame being provided with a movable back, a source of light in one of said compartments, means for automatically opening the back of the frame when brought into registry with one of said openings and for automatically closing the back of the frame when brought into registry with the other of said openings, and means controlled by the printing frame for illuminating the source of light when said frame is in registry with the opening of the compartment within which the source of light is positioned.

In testimony whereof I have signed my name to this specification in the presence of two subscribing witnesses.

GEORGE GRANTHAM BAIN.
